ERASING DEVICE

Edouard Bernier, Chicago, Ill., assignor of one-half to George A. Scheibel, Wilmette, Ill.

Application February 25, 1937, Serial No. 127,735

4 Claims. (Cl. 120—36)

This invention relates to improvements in erasing device, particularly adapted for erasing written matter such as typewriting, and for use by draftsmen for making erasures in drawings, and for other purposes, and one of the objects of the invention is to provide an improved device of this character which will be power driven, and which at the same time will be of a simple, durable and light construction, effective and efficient in operation, and easy to handle.

To the attainment of these ends and the accomplishment of other new and useful objects as will appear, the invention consists in the features of novelty, in substantially the construction, combination and arrangement of the several parts hereinafter more fully described and claimed and shown in the accompanying drawing illustrating this invention, and in which

Figure 1 is a view taken on line 4—4 Figure 2 of a modified form of the invention.

Figure 2 is a sectional view taken on line 2—2 Figure 1.

Figure 3 is a detail perspective view of the eccentric element.

Referring more particularly to the drawing, the device consists essentially of a flexible shaft arranged within a casing 10 and which shaft is connected to any suitable source of power.

At one end of the casing 10 is arranged a frame 11 having an open portion 12 and forming bearings 13 and 14. Into the bearing 13 one end of the casing 10 projects and the end of the shaft 15 which projects beyond the casing 10 is rotatively supported in bearing 14. The end of the shaft projects through and beyond the bearing 14, and may be provided with threads 16.

With this device it will be manifest that the frame 11 will constitute a handle or hand hold by means of which the tool may be manipulated.

In use the shaft is rotated from a suitable source of power which will rotate the eraser 17. By grasping the casing or frame 11, and while the eraser is rotated it will be manifest that the latter may be manipulated and placed into contact with the surface to be cleaned or from which the erasure is to be made.

The open space 12 in the frame 11 permits access to the portion 15 of the shaft so that this portion may be gripped with a tool or in any manner to hold the shaft against rotation while the member 20 is being screwed onto or off of the threaded end 16.

In the present exemplification of the invention there is provided a casing comprising two sections 18 which may be fitted together by tongue

and groove joint and then secured against separation by means of a suitable fastening device 19 such as a screw or the like.

The casing 18 is preferably of a substantially inverted L shaped configuration and the end of the shaft on which the threads 16 are provided projects through the bearing 14 and into the casing.

Secured upon the thread 16 is a member 20 having a pin 21 extending beyond one end thereof which is arranged eccentrically with respect to the axis of the member 20.

The numeral 22 designates a lever which is arranged in the portion of the casing 18 that is disposed at an angle to the portion in which the member 20 is arranged. This lever 22 is pivotally mounted intermediate its ends as at 23 and the upper extremity of the lever is bifurcated as at 24 and is so positioned that the eccentric pin 21 will project into the bifurcation.

The free extremity of the lever 22 terminates at substantially the lower end of the casing 18 and the walls of this portion of the casing are provided with slots 25 so as not to interfere with the movement of the lever 22 about the pivot 23. The lower end of the lever is preferably tubular as at 26 and into this tubular portion one extremity of the erasing element 27 projects.

In operation the casing 18 is grasped in the hand so as to position the element 27 with respect to the work.

When the shaft is rotated the element 20 will be rotated and this in turn will rotate the eccentrically mounted pin 21 to rock the lever 22 back and forth about the pivot 23.

By grasping the casing 18 it will be prevented from rotating with the shaft.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A device of the character described embodying a flexible shaft, bearings spaced a substantial distance from each other, a member connecting said bearings and forming therewith a side opening frame, the end of said shaft being journaled in said bearings and extending across the frame, a support, a lever pivoted to the support, a tool holder at one end of the lever, and means detachably and operatively connecting the other end of the lever with said shaft, the said mem- 55

ber between the bearings serving as a hand hold whereby to manipulate the said tool, the open side of the frame affording access to the shaft between the bearings, whereby the shaft may be gripped and held against rotation while the tool is being attached or detached from the shaft.

5 2. A device of the character described embodying a flexible shaft, bearings spaced a substantial distance from each other, a member connecting 10 said bearings and forming therewith a side opening frame, the end of the shaft being journaled in said bearings and extending across the frame, an open ended housing, one end of the housing abutting and disposed in alinement with one of 15 said bearings, a lever pivoted intermediate its ends and disposed in said housing, a connection between one end of the lever and said shaft, said connection being disposed in the housing, and a tool holder at the other end of the lever, said 20 member between the bearings serving as a hand hold whereby to manipulate the tool which is connected to the lever, said open side of the frame affording access to the shaft between the 25 bearings whereby the shaft may be gripped and held against rotation.

3. A device of the character described embodying a flexible shaft, bearings spaced a substantial distance from each other, a member connecting 30 said bearings and forming therewith a side opening frame, the end of the shaft being journaled in said bearings and extending across the frame, an open ended housing, one end of the housing abutting and disposed in alinement with one of 35 said bearings, a lever pivoted intermediate its ends and disposed in said housing, a

connection between one end of the lever and said shaft, said connection embodying a member disposed in the housing and threaded upon the end of the shaft, a connection between the last said member and the lever to rock the lever, and a 5 tool holder at the other end of the lever, the first said member between the bearings serving as a hand hold whereby to manipulate the tool which is connected to the lever, said open side of the frame affording access to the shaft between the 10 bearings whereby the shaft may be gripped and held against rotation.

10 4. A device of the character described embodying a flexible shaft, bearings spaced a substantial distance from each other, a member connecting 15 said bearings and forming therewith a side opening frame, the end of the shaft being journaled in said bearings and extending across the frame, an open ended housing, said housing being divided longitudinally, means separably securing the 20 parts of the housing together, one end of the housing abutting and disposed in alinement with one of said bearings, a lever pivoted intermediate its ends and disposed in said housing, a connection 25 between one end of the lever and said shaft, said connection being disposed in the housing, and a tool holder at the other end of the lever, said member between the bearings serving as a hand hold whereby to manipulate the tool which is connected to the lever, said open side of the 30 frame affording access to the shaft between the bearings whereby the shaft may be gripped and held against rotation.
